[57] CLAIM

The ornamental design for a telephone handset, as shown and described.

DESCRIPTION

FIG. 1 is a perspective view of a telephone handset showing my new design with the receiver and speaker portions in a first and closed position;

FIG. 2 is a front elevational view of the telephone handset with the receiver and speaker portions in the first or closed position;

FIG. 3 is a side elevational view of the telephone handset with the receiver and speaker portions in the first or closed position;

FIG. 4 is a bottom plan view of the telephone handset;

FIG. 5 is a top plan view of the telephone handset;

FIG. 6 is a rear elevational view of the telephone handset with the receiver and speaker portions in the first or closed position;

FIG. 7 is a perspective view similar to that shown in FIG. 1 but with the speaker and receiver portions of the telephone handset in a second or extended position relative to each other; and,

FIG. 8 is a perspective view, similar to that shown in FIG. 7, of a second embodiment of the telephone handset with the speaker and receiver portions in an extended relationship to each other.
